UNITED STATES PATENT OFFICE.

CLARENCE W. BENNETT, OF NEW YORK, N. Y.

VELOCIPED.

1,373,707.

Specification of Letters Patent.

Patented Apr. 5, 1921.

Application filed January 14, 1920. Serial No. 351,385.

To all whom it may concern:

Be it known that I, CLARENCE W. BENNETT, a citizen of the United States, residing at New York city, in the county and State of New York, have invented certain new and useful Improvements in Velocipedes, of which the following is a specification.

This invention relates to vehicles of the type ordinarily known as velocipedes and has reference particularly to the wheel hub and crank structure.

The objects of the invention are to provide a simple, practical and relatively inexpensive structure of this character which can be readily assembled and particularly one in which the cranks can be easily removed for shipment and storage purposes and which, when desired, can be as readily assembled.

The invention involves various novel features of construction, combinations and arrangements of parts, all of which will be fully described in the following specification which is to be read in conjunction with the accompanying drawing forming a part hereof and wherein I have disclosed but one of the preferred embodiments of the invention.

In the drawing referred to, Figure 1 is a perspective view of a child's velocipede having the features of the invention incorporated therein.

Fig. 2 is a cross sectional view of the hub structure of the front wheel, as taken on substantially the plane of line 2—2 of Fig. 3.

Fig. 3 is a broken and longitudinal sectional view of the hub and crank assembly.

Fig. 4 is another cross sectional view taken on substantially the plane of line 4—4 of Fig. 3.

Referring now to the several parts in detail, 5—5 designate the arms of the so-called "fork" which are provided at their lower ends with suitable bearings 6 to take the journal or axle portions 7 of the cranks 8.

These cranks are interlocked or keyed to the hub structure by means of non-circular keying portions 9 provided at the inner ends thereof which take into correspondingly shaped seats in the ends of the hub. These seats are provided by means of a tubular member, designated 10, of non-circular cross section and shown, in the

illustration, as flattened (Figs. 2 and 4) to fit the correspondingly flattened keying portions 9 of the cranks.

In the present disclosure this tubular member 10 is also utilized as a means for securing the end heads of the hubs together, the ends of said tube being shown as extending through non-circular openings in the end heads 11 and riveted or turned over at the outer faces of the same, as indicated at 12. The heads are held apart in proper spaced relation by a suitable spacing sleeve 13 which, like the heads and tube, may be constructed of relatively light and inexpensive sheet metal.

Spokes 14 are suitably secured to the end heads, in this instance, by overlying clamping plates 15 which are held in place by tongues or flanges 16 extended from the heads between the spokes and bent over the outer face of the clamping plates—see particularly in this connection Fig. 4.

The cranks are detachably secured to the hub by means of nuts 17 rotatably confined to the outer ends of the hubs and engaging with screw-threaded portions 18 provided on the cranks between the journal portions 7 and the keying ends 9 thereof (Fig. 3). For rotatably securing these nuts in place I have illustrated in the present disclosure cap plates 19 fastened to the end heads by means of inwardly struck fingers or flanges 20 extended in between the spokes and bent over the inner faces of the heads, said caps having radially projecting annular flanges 21 overlying the annular outstanding flanges 22 of the nuts. The fit of these parts is such that the nuts are centered with respect to the wheel hub and while firmly held thereto, are free to be turned by means of a suitable wrench for instance.

The construction described provides a rigid, strong hub structure which is relatively light and inexpensive to manufacture and provides a means by which the cranks may be readily attached or detached, as required. In mounting the wheel in the fork, the wheel is centered between the arms of the fork, the cranks are entered through the bearings provided therefor and when the threaded portions of the cranks are engaged by the nuts, the nuts are turned on the hub to thereby advance the keying portions on the inner ends of the cranks into the seats provided therefor in the hub, care being exercised in the first instance to place

the cranks so that the keying portions will properly register with the seats therefor. When the cranks are to be detached, the nuts are simply turned in the reverse direction 5 so as to withdraw the keying portions from the key-seats in the hub.

While the above constitutes a practical and at the present time a preferred embodiment of the invention, it will be understood 10 that various modifications may be made without departure from the spirit and scope of the invention defined in the appended claims and I would furthermore have it understood that the terms employed herein 15 are used in a descriptive rather than in a limiting sense, except, however, for such limitations as may be imposed by the state of the prior art.

What I claim is:

20 1. In combination with a velocipede, a fork provided with bearings, a wheel in said fork, a hub for the wheel, said hub having non-circular seats in the opposite ends thereof, cranks having non-circular end portions 25 for interlocking engagement in said seats, screw-threaded portions on the crank, journal portions on the crank for engagement with the bearings, and nuts rotatably confined to the opposite ends of the wheel hub 30 and engaging the threaded portions of the cranks to draw the inner ends of the cranks into the seats in the hub and the journal portions into the bearings in the fork.

35 2. In a velocipede, a wheel hub having non-circular seats in the opposite ends of the same, cranks having non-circular end portions for keying engagement in said seats, the cranks being provided with screw-threaded portions, and nuts rotatably confined 40 to the ends of the hub and engaging the screw-threaded portions of the cranks to force the ends of the cranks into the seats aforesaid.

45 3. In a velocipede, a wheel hub having non-circular seats in the opposite ends thereof, bearing members having journal portions, cranks provided with screw-threaded portions, non-circular end portions on the cranks for engagement in the seats aforesaid, and nuts rotatably confined to the ends 50 of the hubs and engaging the screw-threaded portions of the cranks.

55 4. In a velocipede, a wheel hub having end heads, a tubular member extending between said heads and having non-circular end portions, cranks having non-circular end portions fitting in the non-circular end portions of the tubular member, said cranks being provided with screw-threaded portions, and nuts rotatably confined to the end 60 heads and engaging the screw-threaded portions of the cranks.

65 5. In a velocipede, a wheel hub having end heads, a spacing sleeve between said heads, a tubular member having non-circu-

lar ends secured in said heads and fastening the same together, nuts rotatably confined to said end heads, and cranks having screw-threaded portions engaged by said nuts and non-circular end portions fitting in the non-circular ends of the tubular member. 70

6. In a velocipede, a wheel hub having end heads, a spacing sleeve between said heads, a tubular member having non-circular ends secured in said heads and fastening the same together, flanged nuts overlying said end heads, caps secured to the heads and having flanges overstanding the flanged nuts to rotatably confine the same to said heads, and axle members having screw-threaded portions engaged by said nuts and non-circular end portions fitting in the non-circular ends of the tubular member. 75

7. In a velocipede, end heads carrying non-circular seats, spokes secured to said heads, nuts rotatably confined to said heads, and axle members having screw-threaded portions engaged by said nuts and non-circular end portions fitting in said seats. 80

8. In a velocipede, a wheel hub comprising end heads, a spacing sleeve between said heads, a non-circular tube extending between said heads and secured thereto at its ends, spokes secured to the end heads, flanged nuts overlying said heads, caps secured to the heads and having flanges rotatably confining the nuts, and axle members having screw-threaded portions engaged by said nuts and non-circular end portions fitting into the ends of the non-circular tube. 90

9. In a velocipede, a wheel hub assemblage comprising end heads, a spacing sleeve between said heads, a non-circular tube extending between the heads and secured thereto at its ends, spokes applied to the end heads, clamping plates, securing said spokes to said heads, nuts applied over said plates and provided with outstanding flanges, caps secured to the heads and having flanges overstanding the flanges of the nuts, and axle members having screw-threaded portions engaged by said nuts and non-circular end portions fitting into the non-circular ends of the tube. 95

10. In a wheel hub, end heads, means securing said heads together in spaced relation, spokes applied to said end heads, clamping plates applied over said spokes, flange members extending from said heads and engaged over the clamping plates, and end caps applied over the clamping plates and having flange members secured over the end heads. 110

11. In a wheel hub, end heads, means securing said heads together in spaced relation, spokes applied to said end heads, clamping plates applied over said spokes, flange members extending from said heads and engaged over the clamping plates, end 115 caps applied over the clamping plates and having flange members secured over the end heads.

12. In a wheel hub, end heads, means securing said heads together in spaced relation, spokes applied to said end heads, clamping plates applied over said spokes, flange members extending from said heads and engaged over the clamping plates, end 120 caps applied over the clamping plates and having flange members secured over the end heads.

caps applied over the clamping plates and having flange members secured over the end heads, and flanged nuts held to the ends of the hub by said caps.

5 12. In a wheel hub, an end head, spokes applied thereto, a clamping plate applied over said spokes, fingers extending from the head between the spokes and engaged over the clamping plate and a cap applied over 10 the clamping plate and having fingers extending over the fingers of the head and bent over the back of the head.

13. In a wheel hub, a head plate and a clamping plate, spokes engaged between 15 said plates, said head plate having fingers extending to and bent over the clamping plate, and a cap plate having securing

fingers extending over the first mentioned fingers.

14. A wheel hub having a non-circular seat in one end thereof, an axle member having a non-circular end portion fitting said seat, said axle member being provided with a screw-threaded portion, and a nut rotatably confined to the hub and engaging 25 the screw-threaded portion of the axle member to force the non-circular portion thereof into the seat provided therefor.

In testimony whereof I have affixed my signature in presence of two witnesses.

CLARENCE W. BENNETT.
